FIG. 1

FIG. 2

FIG. 3

FIG. 1 is a top plan view of an electronic calculator showing our new design.

FIG. 2 is an end elevational view of the same.

FIG. 3 is a side elevational view of the same.

The side of the calculator which is not shown is a minor image of the side which is shown in FIG. 3.

Representative key caps and control switches are shown. The peripheral edge strip is of a material which contrasts with that used on the other surfaces of the calculator such as a chrome strip or the equivalent.

We claim:

The ornamental design for an electronic calculator, as shown and described.
